ASH TRAY STAND

Salvador G. Messina, Baton Rouge, La., assignor to
Messina Smoking Stand, Inc., Baton Rouge, La., a cor-
poration of Louisiana

Filed Aug. 21, 1964, Ser. No. 81,393

Term of patent 14 years

(Cl. D85—2)

Fig. 3

Fig. 4

FIGURE 1 is a side elevational view of an ash tray stand, showing my new design;

FIGURE 2 is a front elevational view;

FIGURE 3 is a top view; and

FIGURE 4 is a sectional view taken on the line 4—4 of FIGURE 1.

The dominant feature of my design resides in the portions shown in full lines.

I claim:

The ornamental design for an ash tray stand, substantially as shown and described.
